APPARATUS FOR SUEDED CLOTH

George M. Curtin, Gloversville, N. Y.

Application June 28, 1939, Serial No. 281,631

10 Claims.

(Cl. 26—28)

This invention relates to a method and apparatus for sueding cloth in strips of unlimited length.

Sueding of cloth involves the cutting or breaking of part of the strands comprising the threads of the cloth thus improving the feel and to some extent the appearance of the cloth. Heretofore it has been attempted to pull a piece of cloth across the face of a number of abrasive rolls arranged in series but unsatisfactory results have been obtained due to the fact that the cutting or breaking of the strands of the threads of the cloth has occurred to an undesired degree, and due to the fact that in pulling the cloth past the abrasive surfaces portions of the width of the cloth have been stretched out of proportion to other portions of the cloth and the edge portions have been curled preventing satisfactory sueding.

In carrying out my invention I provide a simplified structure wherein a single abrasive drum may be employed, and the cloth positively advanced by the abrasive drum in cooperation with a presser roller. Means are provided interposed between the cloth and abrasive surface to control the length of cloth in contact with the abrasive surface at any moment; auxiliary means for separating the cloth from the abrasive surface are provided, and means for folding the cloth are made adjustable in stroke and synchronous with the combined speeds of the abrasive and presser rolls, regardless of wear of either or both of them.

By my invention I have provided an improved method and means for sueding long strips of cloth making possible higher speed production than heretofore obtained with resultant lower cost; whereby the quality of the sueded cloth may be greatly improved and a smoother finish obtained and whereby the curling of the edges heretofore experienced is obviated making it possible to obtain satisfactory sueding of the full width of a strip of cloth.

The invention will best be understood if the following description is read in connection with the accompanying drawings in which:

Figure 1 is an elevation of one end (motor end) of the machine;

Figure 2 is an elevation of the other end of the machine;

Figure 3 is a front elevation;

Figure 4 is a rear elevation;

Figure 5 is a side view, partly in section, including the folding means and showing the course of a strip of cloth through my device;

Figure 6 is a sectional view through the folding device taken on line 6—6 of Figure 5; and

Figure 7 is a detail view, partly broken away, of the feed table over which the material passes to the abrasive roll.

Referring first to Figure 5 the letter M indicates a long strip of cloth which is being continuously sueded and folded in accordance with my invention. The strip of cloth may be of unlimited length. My invention also makes it possible to successfully suede strips of cloth of unusual width. Strips of cloth five feet in width have been very successfully treated in a machine embodying my invention and the invention is applicable to machines capable of sueding cloth of even greater width.

The cloth to be sueded may be brought to the sueding machine upon a truck in a vertical column of folds, or it may be wound on rolls supported so that the cloth may be readily unwound therefrom, or may be supplied in any other desired manner. It is led into contact with the surface of abrasive drum 10 by being passed over pressure roller 11. These two drums are positively driven in opposite directions at different speeds so that the cloth is positively engaged between the surfaces of the two drums and is driven forward, and at the same time one surface of the cloth is subjected to the cutting action of the surface of abrading drum 10.

The length of time that any portion of the cloth is in contact with the surface of abrading drum 10 is controlled by passing the cloth around a bar 12, located below the point of contact of abrasive drum 10 and pressure roller 11, and adjustable toward or away from the abrasive drum. By adjustment of the position of guide bar 12, and of the degree of pressure with which the cloth is pressed against the surface of the abrasive drum 10 by the roller 11, as will be explained, the extent to which the cloth is sueded may be carefully controlled and an improved sueded product obtained regardless of the thickness of the cloth being treated. As illustrated the sueded cloth, after leaving bar 12, passes under an idler 13 and is then looped over friction roller 14 which is given a peripheral speed equal to that with which the cloth leaves abrasive drum 10. Means are provided, as will be explained, for adjusting the speed of roller 14 to accommodate for change in the speed given to the cloth by feed roller 11 and abrasive drum 10, due to wear of said feed roller and drum.

From friction roll 14 the cloth is advanced to a pivoted folding device which is synchronized with the speed of the cloth and directed between two idler bars 15 extending between arms 16 with the result that the sueded cloth is folded in a vertical column of folds, which as indicated may be piled on a truck 17 for convenience in handling.

The machine, referring first to Figures 1 to 4, comprises a base 20 on which are erected side frames 21 and 22, which in turn are braced by transverse members 23 and 24. Mounted on the

rearward portion of the upper surfaces of the side frames 21 and 22 are bearing brackets 25 and 26 which journal the trunnions 27 and 28 of the abrasive drum 10.

Pressure roller 11 is mounted so as to be adjustable toward or away from abrasive drum 10, being journaled in slideable pillow blocks 30 and 31 which are guided in recesses 32 and 33, provided for this purpose in the base of slideable pillow block supports 34 and 35. Rotatably connected to collars 36 and 37 of bearing blocks 30 and 31, and journaled close to their opposite ends in the hub portions 45' of the handwheels 45, are the spindles 38 and 39 which have at their extreme forward ends the turn knobs 42. Screwed to the spindles 38 and 39 are collars 38', and around the spindles the compression springs 45'' are provided extending between the collars 38' and the shoulders of the hub portions 45' which are threaded in the upright portions 40 and 41 of the supports 34 and 35. By turning the handwheels 45 with their integral hub portions 45' the pillow blocks 30 and 31 may be moved toward, or away from, the abrasive drum 10, the interposed springs 45'' acting as resilient means in case of unevenness in the material being sueded. The adjustment of the handwheel 45 is controlled by calibrations 43 provided on the exterior of hub 45, which is preferably marked off in divisions of one thousandth of an inch, which may be aligned with the marker 44. By means of turn arms 42 the position of the collars 38' on spindles 38 and 39 may be varied thereby adjusting the tension of the springs 45''.

The bearing block supports 34 and 35 have downwardly extended portions 46 which engage undercut flanges 47, machined in the forward portion of the upper surfaces of the side frames 21 and 22. Recesses 48 are provided in the bottom portion of supports 34 and 35 in which snugly engage the anti-friction rolls 49 of the bell crank 50. The latter, pivotably mounted on studs 51 which protruded inwardly from both frames 21 and 22, are connected by arms 52 to the foot treadle brackets 53, keyed to rock shaft 55, between the forward ends 56 of which is supported rod 57, on which the foot treadle 59 is mounted by means of brackets 58.

Keyed also to the rocking shaft 55, which is journaled in bearings 60 of the side frames 21 and 22, are the rearwardly extending pair of arms 61 between which is suspended a transverse rod 62 on which counter weights 63 may be mounted. The counter weights 63, through arm 61, turn buckle links 54 and toggle arms 52 and 50, pull the bearing block supports 34 and 35 rearwardly thus urging the presser roller 11 toward the abrasive roller 10 until the stops 34' abut against the frame members 21 and 22.

In order to move the pressure roller 11 away from abrasive roll 10 the operator steps upon treadle 59 thus overcoming the pull exerted by counter weights 63.

Above the pressure roller 11 the pinch roller 64 is suspended by means of a pair of brackets 25 and 26. The height of the pinch roller may be adjusted in accordance with the thickness of the material to be sueded by means of elevating screws 67 threadedly engaged in brackets 65 which bear against the banking surfaces 68 on the upper surface of the bearing brackets 25 and 26. Diagonally disposed lock screws 69 are threaded in stationary lugs 70 of the bearing brackets 25 and 26 and bear against the surface

71 thus securing the pinch roller 64 in its adjusted position.

The material to be treated is passed over an entrance table 72 supported by end brackets 73 adjustable vertically in stationary hubs 74. The upper surface of the table 72, illustrated in Figure 7, may be provided with ribs 75, inclined outwardly from the center of the table, which tend to open and smooth out the material just before it becomes engaged between presser roll 11 and pinch roll 64.

The control bar 12, is slideably mounted in slots 78 provided in the frame members 21 and 22, by means of brackets 16 having flanges 77. The slots are preferably curved so that the radii of each slot has its center in the axis of the abrasive drum 10. Graduations 79 on the outside of both slots 78 and locking nuts 79a assure perfect parallel alignment of the control bar 12. As illustrated the slots 78 permit bar 12 to be positioned so that any desired contact between the cloth and the abrasive drum 10, ranging from a point of contact to one in which the cloth engages 60 degrees of the surface of the abrasive drum, may be obtained. Of course longer slots may be provided if a greater length of contact is desired.

Suspended from two brackets 85 a transversely extending tube 84, equipped with a plurality of equally spaced holes 83 is provided, which may be connected to a supply of compressed air through flexible hose 86. Tube 84 is positioned so that the blast of air therefrom will be directed between the under surface of the abrasive drum 10 and the finished surface of the material serving thereby both to clean the surface of the drum, and to separate the material from the drum if it should become engaged therewith beyond the point for which control bar 12 is adjusted. To attain a more effective operation of this device, the perforated tube may be oscillated a distance equal to the distance between two adjacent holes 83, and accordingly brackets 85 are supported by an oscillating rod 87, which is journaled in two dust-sealed bearings 88.

Fastened on both ends of the rod 87 and guided over idling sprockets 89a and 90a are link chains 89 and 90, the former being connected to the link 92, pivotally connected to the crank 93 of the speed reducing unit 94, and the latter being connected to counterweight 95 which serves to return the rod 87 to its end position whenever the position of the crank 93 permits it to do so. A cylindrical guard 96 is provided for suspended counterweight 95.

A speed reducer 94 is supported by the bracket 97, fastened to the frame 22. Supported also from the frame 22 is a bracket 98 on which are provided two bearings 99 and 100 between which the intermediate shaft 101 is suspended. The latter is driven by a variable speed pulley 102, the V-shaped annular groove 103 of which can be narrowed or widened so as to permit the V-belt to engage under different radii of contact with the pulley for the desired variation in speed. This variable pulley, rotating on a sleeve 104 (not shown) which is fitted to the shaft 101, is longitudinally located on one side by shoulder 102a on shaft 101, and by a collar 101a on the other side. The variable space between the two halves of the pulley caused by the variations in the width of groove 103, is taken up by a self adjusting spring, coiled in the inside of the two halves of the pulley 102. To the outer side of this adjustable pulley is fixed a male member 105

of the jaw clutch 106, the female member 107 of which is slideably keyed or splined to the shaft 101 and urged in continuous engagement by the surrounding coil spring 108. The female clutch member 107 has an annular groove 109 in which engage two studs 110 of a yoke 111. Yoke 111 is fixed to the shaft 112, journalled in a double bearing 113, suspended from bracket 114 on frame member 22. The shaft 112, has a portion extended beyond bearing 113 on which is mounted an actuating lever 115. The latter has at its lower end a cam surface 116 against which acts the treadle bracket extension or cam follower 117, rendering the shaft 101 idle when the pressure roller is moved out of operative position relative to the abrasive drum, thus rendering inoperative the folding mechanism which is described herein. Secured to shaft 101 is sprocket 118 and pulley 119. The sprocket 118 relays motion by means of chain 118a to a sprocket 120 on short intermediate shaft 120 from which the take off roller 14 is driven by means of sprocket 133 and chain 135. Pulley 119 transmits rotation to the pulley 122a of the variable speed changer 122 to be described later, which is supported by two brackets 123 from the vertical pillar 124 of the folding device frame work 125.

The frame 125 comprises besides the pillar 124, a similar pillar 126 on the opposite side of the machine the lower ends of which are secured to the frames 21 and 22, and two horizontal supports 127 fixed to the upper ends of the pillars 124 and 126 respectively, the other ends of which are suspended from the ceiling 129 by two vertical studs 127.

To further the rigidity of the frame work 125, angle profiles have been chosen for the frame members, the angular flanges providing in the case of the vertical pillar 124 a protective guard for the various short shafts and chains, and in the case of the horizontal girders 127, a mounting surface for bearings and brackets. The take off friction roller 14, journalled in a pair of pillow block bearings 131 and 132, extends beyond one of the bearings so that the sprocket 133 can be fastened to shaft 14. Sprocket 133 and collar 134 are closely fitted to the outside of the respective pillow blocks and thus serve to brace the structure 125. The sprocket 133 is actuated by the chain 135 and sprocket 136 which is keyed to the same intermediate shaft 120 as the sprocket 121. The rocking shaft 130 with the swinging frame 16 fixed thereto, is journalled in two pillow block bearings 137 and 138 which in turn are mounted on elevated surfaces of brackets 139. One end of the shaft 130 is extended beyond bearing 138 and has rigidly connected thereto the rocking arm 140, which in co-operation with the collar 141 at the opposite end of the shaft 130, and the two hubs 142 of the pivoted frame 16, assists in bracing the structure transversely at that point.

Two counterweights 143, adjustably mounted on the two arms extending from the hubs 142, counterbalance the frame 16. For adjusting the appropriate angle within which the latter is to swing, the rocking arm 140 is provided with an elongated aperture in which can be adjustably secured a shouldered stud 144 by means of the lock nut 145. The arm 140 is rocked back and forth by the connecting rod 146, which has its opposite end journalled on the stud 147, eccentrically located on the rotating disc 148. The latter is keyed to the short shaft 149, journalled in the wide bearing block 150 and longitudinally

secured by the hub 151 of disc 148 and the sprocket 152 at its opposite end. The latter is rotated by a chain 153, driven from the intermediate shaft 154 which is journalled in the pillar 124 and to the opposite end of which is pinned the pulley 155. This pulley is driven by the belt 156a from the pulley 156, mounted on the same shaft of the variable speed changer 122 as the pulley 122a.

Referring now to Figure 4, the handle 157, extending through the diagonal slot 158 of the speed changer 122, can be adjusted so as to control the differential mechanism of the speed changer. The two outer halves 159 and 160 of the pulleys 122a and 156 are mounted on the inner or solid shaft 161, and are longitudinally shifted the same distance in one direction, as the tubular shaft 162, to which are pinned the inner halves 163 and 164 of the pulleys 122a and 156, is moved in the opposite direction. As a result, one of the V-shaped grooves 165 will be narrowed and the other widened. Consequently the V-belt on the narrowed pulley will contact the said pulley on a larger radius in the same proportion as the V-belt of the widened pulley reversely will contact the latter on a smaller radius. Thus the belt connected to the narrowed pulley will be slightly lengthened the same distance as the belt on the widened pulley will be shortened, and these differences will be equalized by the spring pressed belt tighteners 159b and 156b, which in case of the shortened belt will yield, and in case of the lengthened belt will take up the slack.

To prevent the abrasive drum 10 from continuing to rotate after the motor has been shut off, a hand brake 166, connected to a hand lever 167, pivoted at 168, has been provided and is normally pulled against the adjustable stop 169 by the spring 190.

The driving mechanism for the previously described elements is best illustrated in Figures 1, 2 and 3. As shown in Figure 1 and Figure 3 the base 20 has an extension base 166 with a bracket 167 to which is hinged at 168 the adjustable motor platform 169. The latter can be raised or lowered for the proper tensioning of the multiple V-shaped driving bolts 170 by tightening or loosening swing bolt 171, shown in Figure 1. The multiple belt 170 relays rotation from the multi-grooved pulley 171a to the abrasive drum 10 at reduced speed by means of multi-grooved driving pulley 172. The multi-step pulley 173, keyed to the opposite end of the abrasive drum 10, transmits motion at a still more reduced speed to another multi-step pulley 174 mounted on shaft 175 to which is keyed the gear 176 which is in mesh with its mate 177 on the adjacent intermediate shaft 178. Fixedly connected to this shaft 175 is the pulley 179 which through the medium of belt 180 rotates the pulley 181 of the speed reducing unit 94 of the air jet device 82. The intermediate shaft 178 has fixed thereto on one end the multiple pulley 182, which through the multiple belt 183 rotates the pressure roller 11 at a still more decreased speed. The shaft 172 carries at its opposite end, Figure 3, another pulley 184 which through the medium of belt 185 causes the variable synchronizing shaft pulley 102 to revolve.

It will be seen that a device embodying my invention has the great practical advantages of accurate coordination between the feeding and the folding of the cloth being sueded, at all times, and regardless of wear of the parts, particularly the pressure roller; and of ready means for con-

trolling and changing the size of the folds during the operation of the device, in addition to the advantages of the improved quality of the sueded cloth made possible by my invention.

What I claim is:

1. Apparatus for sueding a long length of cloth comprising in combination an abrasive drum, a presser roller cooperating therewith, means for rotating said abrasive drum and said presser roller, means for directing said length of cloth between said drum and roller, a member extending transversely across the path of travel of said length of cloth beyond the point of nearest approach between the drum and roller, and means for adjusting said member through an arc all points of which are equidistant from the axis of said drum.

2. Apparatus for sueding a long length of cloth comprising in combination an abrasive drum, a presser roller moveable toward or away from the abrasive drum, means for rotating said abrasive drum and said presser roller in opposite directions and at different speeds, adjustable means for guiding the cloth to control the length of cloth in contact with the abrasive drum at any one time, and means supplementary to said cloth guiding means for separating portions of the cloth adhering to the surface of the drum beyond the desired point of separation as indicated by said guide means.

3. Apparatus for sueding a long length of cloth which comprises an abrasive drum and a pressure roller cooperating therewith, means for directing a long length of cloth between said drum and roller, means for actuating said drum and roller to cause the length of cloth to be continuously propelled thereby, guide means located beyond the point of engagement of the cloth between said drum and roller, and means for varying the position of the guide means through an arc concentric with the axis of the abrasive drum whereby the length of the contact between the cloth and the surface of the abrasive drum may be controlled.

4. Apparatus for sueding cloth comprising in combination an abrading drum, a presser roller moveable toward or away from the abrading drum, means for engaging the cloth after it has passed between said drum and roller, and means for adjusting said engaging means to vary the contact between the cloth and drum from a line of contact to one in which the cloth engages 60° or more of the surface of the abrasive drum.

5. Apparatus for sueding cloth comprising in combination an abrading drum, a presser roller moveable toward or away from the abrading drum, adjustable means for engaging the cloth after it has passed between said drum and roller and for varying the area of contact between the cloth and drum, and means independent of said cloth engaging means for separating portions of the cloth adhering to the surface of the abrasive drum beyond the point of separation indicated by the position of said cloth engaging means.

6. Apparatus for sueding cloth comprising in combination an abrading drum, a presser roller, a pinch roller arranged above said drum and presser roller in position to aid in directing a strip of cloth between said presser roller and abrasive drum, and guide means located below said abrasive drum and presser roller for separating

the cloth from the surface of the abrasive drum at a predetermined distance from the point of nearest approach between the said abrasive drum and presser roller.

5. 7. Apparatus for sueding cloth comprising in combination an abrading drum mounted on a fixed axis, a presser roller mounted on an axis moveable in the common plane of its axis and the axis of the abrading drum, a pinch roller mounted on an axis which is moveable substantially in a plane normal to the aforesaid plane, clamping means for clamping said pinch roller in adjusted position, cloth guiding means positioned on the side of a plane common to the axis of the abrading drum and feed roller opposite to the pinch roller, and means for adjusting the position of the guide means in a plane substantially parallel to the plane common to the axes of the abrading drum and feed roller.

10 15 20 25 30 35 40 45 50 55 60 65 70

8. Apparatus for sueding cloth comprising an abrading drum, a presser roller, and a pinch roller, means to rotate said abrading drum at a high peripheral velocity, means to rotate said presser roller in the opposite direction at a peripheral velocity slower than that of the abrading drum, means urging said presser roller toward said abrading drum, means mounting said pinch roller for free rotation comprising a pair of pivoted arms, journals in said arms, means to clamp said arms in adjusted position, a guide member extending parallel to the axes of said drum and rollers, and means for adjusting the position of said guide in a plane substantially parallel to the plane passing through the axes of the drum and the feed roller.

9. Apparatus for sueding cloth comprising in combination an abrading drum and presser roller, means for rotating said drum and roller in opposite directions at differential speeds, means located beyond the point of nearest approach between the drum and roller for separating the cloth from the surface of the abrasive drum, and means for directing a blast of air against the drum beyond the desired point of separation of the cloth from the surface of the abrasive drum.

10. Apparatus for sueding cloth comprising in combination an abrasive drum, a presser roll moveable toward or away from the abrasive drum, means for rotating said drum and roller to engage a length of cloth on opposite sides and advance it continuously at a speed different from that of the abrasive drum, guide means located beyond the point of nearest approach between the drum and roller, a folder arm, pivotal mounting means therefor, a take-off roll positioned so as to lead the cloth around the guide means to said folder arm, a crank and crank disc connected to said folder, a drive shaft, means for interconnecting said shaft and said means for rotating the drum and roller, driven means interconnecting the drive shaft and said crank disc, driven means interconnecting said drive shaft and said take off roll, clutch means between said drive shaft and said crank disc and said take-off roll respectively, and means connecting said clutch means with said presser roller whereby said clutch is open whenever the presser roller is moved out of operative relation to the abrasive drum and is closed whenever the presser roller is moved into operative relation to the abrasive drum.

GEORGE M. CURTIN.
